UNITED STATES PATENT OFFICE.

WALTER H. RICHMAN, OF PHILADELPHIA, PENNSYLVANIA.

CONTAINER.

1,895,298.

Specification of Letters Patent. Patented Nov. 1, 1921.

Application filed November 20, 1919. Serial No. 339,436.

To all whom it may concern:

Be it known that I, WALTER H. RICHMAN, a citizen of the United States, and resident of Philadelphia, Pennsylvania, have invented certain new and useful Improvements in Containers, of which the following is a specification.

In the ice cream industry it is a desideratum to have the cans in which the cream is packed free from crevices or ridges on which or in which some of the cream will remain after the can is emptied and cleaned, because if this happens the residue by becoming stale and rancid will deleteriously affect the new pack.

Ice cream cans heretofore, have been constructed in various ways among which may be mentioned the riveted can in which the crevices or spaces resulting from the lapped joint are filled in with solder. This solder filling is objectionable however, because in order to retin a worn can it is necessary first to remove the solder as otherwise the tin bath will become polluted with the solder melted from the seams or crevices, and therefore prevent a pure tin coat being applied.

My improved can is free from crevices or ridges on its interior because of its structure and thus no filling material such as solder need be employed. The can presents a smooth continuous surface at all points and thus prevents the lodgment or retention of any residue when cleaned and furthermore the can is susceptible of retinning without the preliminary step of removing the solder which hitherto has been employed to fill the seams or crevices.

The invention consists in the features or combination and arrangement of parts, hereinafter described and particularly pointed out in the claims.

In the accompanying drawings,

Figure 1 is a vertical sectional view of an ice cream can embodying the invention, part of the body being broken away.

Fig. 2 is a sectional view of the bottom at one stage of its formation.

Fig. 3 is a similar view of the bottom at another stage in its formation.

In these drawings, 1 is the body of the can which is made of a sheet of metal with the edges brought together and butt welded, forming a flush longitudinal seam. The bottom is specially formed to make a closed joint or seam with the body all the way around the same. The flush seam 3 of the

body resulting from the butt welding, edge to edge, contributes to the continuity of the closed seam between the bottom and the body as there is no shoulder or recess left at any point bridged by the edge of the bottom, leaving an opening between.

This bottom is formed by successive actions upon a suitable blank. The result of the first operation is illustrated in Fig. 2 wherein it will be seen that the construction involves an upstanding side 4 of cylindrical form and of an outside diameter corresponding to the inside diameter of the can body, a flange 5 and the main head or bottom 6 of dished form which merges into the cylindrical side by a curved edge 7.

Fig. 3 shows the second step in the formation of the bottom member in which it will be noticed that the curved edge 7 is swaged or pressed so that the dished formation is carried all the way to the plane of the outer cylindrical face of the upstanding side, resulting in the formation of an edge 7' of knife-like sharpness.

The relative diameters of the outside of the cylindrical portion of the bottom and the inside of the body of the can are such that in order to place the bottom member in the cylindrical body in proper position, considerable force must be exerted or in other words, the parts are initially united by a driving fit, the knife like edge 7' scraping along the interior wall of the body and maintaining its close fit therewith. As above stated, the flush seam 3 of the can body resulting from the welding of the meeting edges contributes to the initial assembling action just described, there being no shoulder or recess along the seam 3 which would interfere with the continuity of the close contact around the entire circuit of the edge 7'.

The edge 7' being sharp and terminating in the plane of the outer face of the upstanding side 4 of the bottom member presents a construction which lends itself readily to the formation initially of a close fitting joint between the inner wall of the body and the bottom member, which can not be done if it is attempted to make the bottom with a square corner where it joins its side portion, it being impossible to prevent a slight rounding of this corner in the dies, and a round corner will make a crevice for the lodgment of some of the can's contents therein, and defeat the object of this invention.

Should any minute crevices exist between the sharp edge 7' and the wall of the body due to slight irregularities these can be taken care of by subsequent treatment. Ordinarily these minute crevices will be closed by the tin coating but the closeness of the joint may be assured by the subsequent action just referred to. For instance in affixing the bottom to the body the flange 5 is turned up and pressed against the outside of the body after the bottom has been thrust into the body with the driving fit mentioned, and in this pressing action the body will be subjected to pressure on its exterior substantially opposite the point where the edge 7' lies so that the body will be trued up and forced in against the upstanding side of the bottom and against the edge 7' to close any crevices that may exist. This external pressure may however be exerted by suitable means employed in addition to the flange setting means, and in a different operation if desired.

The flange 5 when pressed against the side of the body will be spot welded thereto.

If desired the sharp fin-like edge 7' may be treated locally by a tool inserted into the can after the bottom is placed in position, said tool being adapted to spin, roll, stamp or press the edge over to insure close contact with the wall of the body.

This spinning or other action which may at the same time grind the edge to facilitate its slight deformation to secure the close fit, will take care of any irregularity in the fit of the sharp edge of the bottom within the body, it being understood that the size and shape of the body as well as of the bottom is subject to slight variation in a mechanical job of this character.

By this form of bottom with its sharp edge 7' the joint will be of a close character initially and may not need the tool work thereon or the pressing in of the body, or if so, only at certain points and the joint will be such that the tinning operation will cover it and present a smooth surface on which none of the contents will lodge in such manner as to remain after the can is subjected to the ordinary cleaning process.

No solder will be necessary at any point and hence the can when the tinning has worn off, is susceptible of being retinned without any preliminary operation of removing solder.

The lid of the can is formed with a slightly flared lower edge to facilitate cen-

tering of the lid in place and also to form substantially a corrugated side to resist the hard usage to which the lid is subjected.

This lid presents a sanitary structure because the slight flare of its lower edge will shed dirt and liquid while adding to the strength of the lid. The flange 5 is beveled off at its upper edge 5' to shed dirt and also to prevent dislodgment of any of the ice pack when the can is withdrawn from the freezer or case in which it is held, surrounded by the freezing material, so that one can, when removed, will leave a smooth walled socket in the freezing material into which another can may be inserted and fit accurately without necessitating clearing away any displaced material.

The handle of the lid is formed with a sharp turn at *a* where its main part connects with its pad *b* so that no crevice will exist here for lodgment of dirt or refuse. The pad *b* is welded to the lid.

The welded side seam of the body also contributes to the sanitary character of the can.

The invention can be used as a milk can, ice can or for other kinds of material.

I claim:

1. A container comprising a body portion, and a bottom having a depressed main part and a doubled back portion forming a downwardly extending vertical flange with a fin-like edge at the junction of and braced by the convergent depressed main part and doubled back portion and lying with its highest point against the inner side of the body to provide a smooth continuous surface at the joint and a tin coating applied molten and covering said joint at the inner side of said body and bottom, said joint being solderless, substantially as described.

2. A container comprising a metal body and a bottom, the latter having a vertical face bearing against the inner side of the body, said bottom being concavo-convex in form with its upwardly directed concave face continued substantially uniformly to the vertical plane of said vertical face forming a fin-like edge at the junction of said concave face, whereby a flush joint is made between the body and bottom, said joint being solderless, and a tin coating applied molten to the body and bottom and covering said joint.

In testimony whereof, I affix my signature,

WALTER H. RICHMAN.
